UNITED STATES PATENT OFFICE.

GEORGE V. MONTGOMERY, OF AMSTERDAM, NEW YORK, ASSIGNOR OF ONE-HALF TO APPLETON S. BRIDGESS.

CARRIAGE-BOW.

SPECIFICATION forming part of Letters Patent No. 407,959, dated July 30, 1889.

Application filed March 1, 1889. Serial No. 301,721. (No model.)

To all whom it may concern:

Be it known that I, GEORGE V. MONTGOMERY, a citizen of the United States, residing at the city of Amsterdam, in the county 5 of Montgomery, in the State of New York, have invented a new and useful Carriage-Bow, of which the following is a specification.

My invention relates to carriage-bows; and it consists in the construction and combination of parts herein described and claimed; and my objects are to construct a carriage-bow that will be strong and durable and cheaply made, and one that is susceptible of a very high polish, and which will present an attractive appearance and be very light. I attain these objects by the mechanism illustrated in the accompanying drawings, in which—

Figure 1 is a front elevation of one of the bows with part in section and showing the 20 metal part extended all the way round the carriage-bow. Fig. 2 is a front elevation of one of the bows with part of the bow in section and showing the metal portion extended part of the length of the bows. Fig. 3 is a 25 front elevation of one of the bows made entirely of compressed paper.

A in the drawings is a carriage-bow made of compressed paper or paper-pulp compressed in the shape of a carriage-bow, and having 30 the exposed or upright parts highly polished. The bow may be made wholly of compressed paper, or it may be re-enforced by a metal center running the whole length of the bow, as seen in Fig. 1, or it may be made with a metallic eye embedded in the compressed paper-pulp at the ends of the bow. This compressed paper can be vulcanized, if desired; but it is not necessary, as the compressed paper alone will be sufficiently compact to 40 polish without being vulcanized.

B is a metal piece bent in the shape of a carriage-bow, and is provided at each end with eyes or lugs C, with which to attach the bows to the vehicle or to each other. This 45 eye may be made in the compressed paper, as seen in Fig. 2, or it may be made of a metallic piece embedded in the end of the compressed paper-bow. When the center metallic piece B is used, the paper part is compressed 50 around it, and its object is to strengthen and re-enforce the paper-bow. Thus I have a carriage-bow which is cheaply made, is durable and susceptible of a very high polish, and is much lighter and easier to handle than other 55 bows. The exposed or upright parts may be

compressed much more compactly than the covered or upper part, so that the covered part can be nailed to with ease and thus readily covered with the top and lining, and the exposed or upright parts can be highly 60 polished.

As I form the entire bow of paper-pulp and not the slats alone, as has heretofore been done, which are connected to wooden bows to which the cover is nailed, it is essential 65 where nails are used that the upper face of the bow to which the cover is nailed should not be so compactly pressed as those portions which are exposed and to which a high polish is given, as before stated.

I do not claim a "carriage-bow slat" consisting of a metal core and a tapered covering of compressed paper-pulp or a tapered core in the carriage-bow slat, as shown and claimed in Patent No. 366,511, dated July 12, 1887, as 70 mine is entirely different in construction. The invention is a carriage-bow, and instead of the metallic center or core being tapered to prevent the compressed paper from slipping off and being confined to the slat alone, 75 the metallic center passes all the way around the bow, and is of the same thickness from end to end, thus enabling me to use an ordinary rod, instead of being compelled to have it made tapering, as shown in the patent 80 above cited. I do not use a slat-iron at all, nor do I use a shoulder on the core to keep the end of the covering protected, but my metallic center runs all the way round the bow; and I do not claim a "bow-slat" at all, 85 but an entire carriage-bow, which is much cheaper and more perfect by reason of the uprights, and the bow part being made in one piece instead of in separate pieces.

Now, what I claim, and for which I ask Letters Patent, is—

1. As an article of manufacture, a carriage-bow composed wholly of compressed paper-pulp, substantially as described.
2. A carriage-bow composed of an outer 100 surface of paper-pulp, having its ends and exposed portions compressed to a high degree to receive a polish, and its upper unexposed surface of a less degree of compactness, for the purpose described.

GEORGE V. MONTGOMERY.
